UNITED STATES PATENT OFFICE.

WILLIAM EPSTEIN AND SAMUEL EPSTEIN, OF NEW YORK, N. Y.

SKIRT.

No. 887,610.

Specification of Letters Patent.

Patented May 12, 1908.

Application filed January 10, 1908. Serial No. 410,114.

To all whom it may concern:

Be it known that we, WILLIAM EPSTEIN, a citizen of the United States, and SAMUEL EPSTEIN, a subject of the Czar of Russia, both residents of the city of New York, borough of Manhattan, in the county and State of New York, have invented a new and Improved Skirt, of which the following is a full, clear, and exact description.

10 The invention relates to wearing apparel, and its object is to provide a new and improved skirt or petticoat, provided with a waistband having an expansible and contractible portion, arranged in such a manner 15 that the waistband readily fits different sized waists, and at the same time insures a proper hang of the garment.

The invention consists of novel features and parts and combinations of the same, 20 which will be more fully described hereinafter and then pointed out in the claims.

A practical embodiment of the invention is represented in the accompanying drawings forming a part of this specification, in 25 which similar characters of reference indicate corresponding parts in all the views.

Figure 1 is a side elevation of the improvement as applied; Fig. 2 is an enlarged side elevation of the same, showing the waistband 30 opened up and part thereof broken out, and Fig. 3 is an enlarged transverse section of the same, on the line 3—3 of Fig. 2.

In skirts or petticoats as now manufactured, it is necessary for the manufacturer 35 to provide and the dealer to keep in stock, a large number of skirts of the same pattern and length but of different waist measure, in order to properly fit customers having different sized waists. In order to render the 40 waistband of the skirt adjustable or elastic, various devices have heretofore been proposed, such devices using mostly elastic means in various ways, but invariably the result is not quite satisfactory, and defects, 45 notably improper hang of the garment, are usually the result. In the improved skirt, hereinafter described in detail, use is made of an elastic band or webbing, completely concealed by the fabric material of which the 50 body of the garment is made, thus requiring no matching of the color of the elastic webbing with that of the body of the skirt, and the latter is provided with a placket at one side or at the hip portion, thus allowing the 55 use of an elastic webbing extending uninterrupted clear across the back of the gar-

ment from one side thereof to the other, to insure a proper hang of the garment, irrespective of whether the garment is used by persons having waists of widely different 60 sizes.

As shown in the drawings, the body A of the skirt or petticoat is provided with a waistband B and a placket C arranged at one side of the body A and extending the 65 usual distance downward from the waistband B, the placket C having a suitable fastening device D at the waistband B for closing the said placket.

The front portion B' of the waistband B is 70 plain and formed of an inelastic woven material, such as that of which the body A is usually made, the front portion A' of the said body A being also plain or non-gathered in contrast to the upper gathered rear portion A² of the body A, as plainly indicated in Figs. 1 and 2.

The rear portion B² of the waistband B is 75 formed of an elastic band or webbing B³ enclosed by the body material A³ forming a 80 continuation of the upper gathered portion A² of the body A, the said inclosing portion A³ being secured to the elastic webbing or band B³ by longitudinal rows of stitches E, at the time the said webbing or band B³ is in 85 a stretched condition. It is evident that when the garment is manufactured and the elastic band or webbing B³ is held in a stretched position and the portion A³ in a 90 non-gathered condition incloses the said webbing, and the two are united by the longitudinal rows of stitches, and when the sewing operation is completed and the elastic band B³ is released, then in contracting it 95 forms the upper rear portion A² of the body A into gathers and also the portion A³, the gathers of the latter, owing to the numerous rows of stitches E, being small in comparison to the gathers of the upper portion A².

From the foregoing it will be seen that by 100 having the slit C at one side or the hip portion of the garment, it is possible to make the entire rear or back portion of the waistband elastic, at the same time producing the gathered rear portion A² in contrast to the 105 non-gathered front portion A' of the body A. It will also be noticed that by this arrangement the entire rear waist portion is free to stretch when the skirt is used on larger waists, without danger of disturbing the 110 uniformity or symmetry in the gathers of the upper rear portion A² of the body A.

By having the elastic webbing B³ covered by the body material A³, the webbing is completely concealed and the entire waistband B appears as of the same material as the body A, and hence it is not necessary to select a webbing of the same color and texture as that of the body A, and the desired uniformity of the body A and waistband B is maintained and the waistband is rendered strong and durable.

Having thus described our invention, we claim as new and desire to secure by Letters Patent:

1. A skirt or petticoat, comprising a body, and a waistband, the front portion of the waistband being inelastic and secured to the front portion of the said body, the entire rear portion of the waistband being elastic and formed of an elastic band, the entire rear upper portion of the said body inclosing the said elastic band and being secured thereto throughout its length while the elastic band is in a stretched condition.
2. A skirt or petticoat, comprising a body, and a waistband, the front portion of the waistband being inelastic and secured to the front portion of the said body, the entire rear portion of the waistband being elastic and formed of an elastic band, the entire rear upper portion of the said body inclosing the said elastic band, and longitudinal rows of stitches securing the said band-inclosing portion to the said elastic band while the latter is in a stretched condition.
3. A skirt or petticoat, comprising a body, and a waistband, the front portion of the

waistband being inelastic and secured to the front portion of the said body; the entire rear portion of the waistband being elastic and formed of an elastic band, the entire rear upper portion of the said body inclosing the said elastic band, and longitudinal rows of stitches securing the said band-inclosing portion to the said elastic band while the latter is in a stretched condition, the said upper front portion of the said body being plain or non-gathered, and the entire upper rear portion of the said body adjacent to the said elastic waistband portion being gathered.

4. A skirt or petticoat, comprising a body having a placket at one side thereof, and a waistband consisting of a front and a rear portion, the front portion being inelastic and secured to the upper front portion of the said body, beginning at the placket and reaching to the opposite side of the body, the said rear portion of the waistband being formed of an elastic band, and an integral extended portion of the rear of the said body, the said extended body portion inclosing the said elastic band and being secured thereto throughout the length of the elastic band and while the latter is in a stretched condition.

In testimony whereof we have signed our names to this specification in the presence of two subscribing witnesses.

WILLIAM EPSTEIN.
